UNITED STATES PATENT OFFICE.

JOHN LALLI, OF NEWARK, NEW JERSEY, ASSIGNOR OF ONE-HALF TO LOUIS FINOCCHI, OF NEWARK, NEW JERSEY.

NON-REFILLABLE BOTTLE.

1,118,206.

Specification of Letters Patent. Patented Nov. 24, 1914.

Application filed November 19, 1913. Serial No. 801,771.

To all whom it may concern:

Be it known that I, JOHN LALLI, a citizen of the United States, and a resident of Newark, county of Essex, and State of New Jersey, have invented certain new and useful Improvements in Non-Refillable Bottles, of which the following is a specification.

This invention relates to a non-refillable bottle and particularly to that class of bottle in which the valve, which seats itself when the bottle is placed upright or when fluid under pressure enters through the neck of the bottle, tilts when the bottle is turned to pour liquid from the bottle, the tilting being limited by a suitable weight, such as a ball, the ball acting as a stop for the sliding of the valve and causing the valve to tilt. The ball is further designed to act as an assurance of the seating of the valve, the ball being designed to rotate circumferentially on the valve when the bottle is handled, as bottles ordinarily are, with tiltings and cantings in its manipulation.

The invention is further designed to provide a flange in the bottle neck, which flange has a passage for liquid, and the bottom surface of the flange and the top face of the valve are so formed as to provide a guideway or channel for the ball to travel around on the valve, but preventing the seating of the ball in the passage of the flange.

The invention is illustrated in the accompanying drawing, in which—

Figure 1 illustrates the top part of a bottle neck of my improved construction, the bottle and its parts being shown in section except for the ball and a small part of the valve. Fig. 2 is a view similar to Fig. 1, but showing the bottle turned to pour liquid from it. Fig. 3 is a section on line 3, 3, in Fig. 1, looking upward, this view omitting the ball, and Fig. 4 is a similar view taken at the same place, but looking downward.

The bottle consists of a body portion 10 of any desired shape, the bottle having a throat 11 which forms the bottom part of the neck, the neck being preferably made in two pieces, the other part being embodied in a spout portion 12 which is fastened to the throat 11 in any desired manner, the drawing showing a juncture by means of screw-threads 13. The bottle neck is provided with a valve-seat, in the form shown in the drawing this seat being formed by the top edge 14 of the throat portion 11, although it

will be understood that the valve-seat may be formed in the bottle neck in other ways. Resting on the valve-seat 14 is a valve 15 which has its bottom edge resting on the valve-seat direct, or it can have a projecting circular bead 16 to fit on the valve-seat.

Depending from the valve is a pendant 17 which is so proportioned as to be of nearly the weight of the valve itself, the reasons for which will be set forth hereinafter. The valve is smaller in diameter than the inside wall 18 of the portion of the bottle neck surrounding the valve, but in order to provide for a positive flow of liquid through the valve when it is opened, I prefer to supply the valve with channels 19. The top face of the valve is recessed as at 20, the recessed portion being circumferential or annular, as clearly shown in Fig. 4. The top surface of the valve has a raised central portion 21, which raised central portion is normally opposite a passage 22 in the flange 23. The flange 23 is located above the valve, and the passage 22, which is shown in the drawing as a single passage, may be made of separate holes, or can be disposed as desired. The flange is recessed as at 24 with a raised portion 25 surrounding the passage 22, whereby the recessed portion 24 is circumferentially disposed, as clearly shown in Fig. 3. Resting on the valve is a ball 26, which ball fits in the recess 20, and the recess 24, and can thus freely revolve around the raised central portion of the valve, but can not mount in the said central portion because the distance between the raised portion 25 and the raised portion 21 is less than the diameter of the ball 26. Above the flange 23 I prefer to mount an upper flange 27 which is provided with openings 28 to permit the passage of fluid, these openings being out of register with the channel in the flange 23 so as to make the route more circuitous and making it more difficult to introduce wires and the like to interfere with the valve mechanism.

The weight or ball 26 acts to more positively close the valve against its seat when it is in the position shown in Fig. 1, particularly when a bottle is about to be set down after it has been used, in which case it is very seldom held absolutely vertical and the canting and tilting to which the bottle is subjected causes the ball to travel around the valve and settle well into its place. When the bottle is tilted the ball immedi-

ately rolls to the lowest point in its travel, and as the tilting increases the ball receives the weight of the valve, as shown in Fig. 2. The valve is held by the ball against its seat 5 more or less tightly on the lower side, but the top side is allowed to tilt over to permit the passage of liquid around the valve and through the channel 22. When the bottle is brought to a horizontal position, the ball stays 10 in the place shown in Fig. 2, but the pendant 17 acts to pull the valve shut, since the ball, with its easy rolling motion, allows the valve to swing to its closed position. As the bottle proceeds toward an upright position the ball 15 is released from the binding, due to the weight of the valve, and is again free to travel around the valve and by this rolling in the recess 20, insures the seating of the valve on the valve-seat. 20 The bottle is made of but few parts and its operation is assured, since the ball cannot possibly become lodged in the channel 22, and it permits a free flowing of the liquid from the bottle, since the ball is al- 25 ways beneath the channel 22 as it rolls around to its place as soon as the bottle begins to tilt, and lies at the bottom or lowest part of its channel or path of travel before the valve tilts. 30 While I have illustrated the spout portion and the throat fastened together by a screw-thread, suitable sealing means can be utilized to permanently secure the spout portion on the throat, and the outlet 29 of the 35 bottle neck can be closed by a cork or any other desired closing means.

Having thus described my invention, what I claim is:

1. A non-refillable bottle comprising a 40 bottle neck with a valve-seat therein, a valve fitting on the seat, a flange in said neck above the valve, the flange having a passage for liquid, and a ball on the valve, the top surface of the valve and the bottom face of 45 the flange being recessed to provide a definite path of travel for the ball and preventing the ball from seating itself in the passage.

Copies of this patent may be obtained for five cents each, by addressing the "Commissioner of Patents, Washington, D. C."

2. A non-refillable bottle comprising a bottle neck with a valve-seat therein, a valve fitting on the seat, a flange in the neck above the valve, the flange having a central passage, and a ball on the valve, the lower face of the flange being raised at the edge of the passage, and the top surface of the valve being raised opposite the passage, the distance between the raised portions of the flange and the valve being less than the diameter of the ball. 50

3. A non-refillable bottle comprising a bottle neck with a valve-seat therein, a valve fitting on the seat, a flange in the neck above the valve, the flange having a central passage for fluid, and a ball on the valve, the bottom surface of the flange being raised at 55 the edges of the passage, the top face of the valve being raised at the center opposite the passage, the distance between said raised portion being less than the diameter of the ball, the ball being thus freely movable 60 around the center of the valve but being prevented from becoming seated in the passage of the flange. 65

4. A non-refillable bottle comprising a bottle neck with a valve-seat therein, a valve fitting on the seat and having a pendant, a flange in the neck above the valve, the flange having a central passage for liquid, the bottom surface of the flange being circumferentially recessed with a raised portion at the 70 edges of the passage, the flange having its top face recessed circumferentially and having a raised portion opposite the passage of the flange, and a ball resting between the recessed faces of the valve and the flange and 75 freely movable circumferentially therein, the ball being of larger diameter than the space between the raised portion of the flange and the valve. 80

In testimony that I claim the foregoing, I 85 have hereto set my hand, this 15th day of November, 1913.

JOHN LALLI.
